WINDING MACHINE

Ernest R. Swanson, Cranston, R. I., assignor to
 Universal Winding Company, Boston, Mass., a
 corporation of Massachusetts

Application August 17, 1932, Serial No. 629,229

26 Claims. (Cl. 242—35.5)

This invention relates to improvements in winding machines for winding cops, cones, cheeses and other forms of packages of yarn, thread, cord or like strand material, hereinafter referred to 5 generally by the term "yarn"; and particularly to winding machines wherein the package is driven by peripheral contact with a drive-roll or drum. More specifically, the invention relates to a machine of the traveling type in which a plurality of 10 winding units are mounted upon a revolvable table or annulus and arranged to travel past a fixed point hereinafter designated the "operator's station".

One object of the invention is to provide a 15 winding machine of the type specified wherein the winding units are carried upon a horizontal ring or annulus caused to revolve about a vertical axis whereby to successively present the units to the operator for doffing the completed cops or 20 packages and replacing them with empty cop-tubes, and for replenishing depleted supply-bobbins with full ones.

Another object of the invention is to provide 25 a machine of the type specified wherein the cops or packages are rotated by frictional contact with drive-rolls or drums and arranged with their supporting spindles extending radially with respect to the axis of the revolving annulus to direct 30 the ends of the package outwardly whereby to facilitate the operation of doffing the packages and the tying-up of the ends from the fresh supplies.

Another object of the invention is to provide 35 a machine of the type specified wherein the individual operating mechanisms of winding units are driven from a common source of power without the intervention of complicated gearing.

Another object of the invention is to provide 40 a machine of the type specified having a simplified mechanism incorporated in the driving means which operates to disrupt the synchronism between the rotating packages being wound and the traversing means, whereby to control the disposition 45 of the turns of winding on the surface of the packages to prevent the formation of bands or "ribbons" in which the yarn coils are crowded or "piled".

Another object of the invention is to provide 50 a machine of the type specified which is highly automatic in operation to require little attention on the part of the operator except for replenishing the supply-bobbins and doffing the wound packages.

Another object of the invention is to provide 55 a machine of the type specified having means for

automatically arresting the winding operation of each individual unit when the yarn breaks or its supply is exhausted and also upon completion of the package to the required size.

Further objects of the improvement are set 5 forth in the following specification which describes a preferred form of construction of the invention, by way of example, as illustrated by the accompanying drawings. In the drawings:

Fig. 1 is a plan view of the improved winding 10 machine on a greatly reduced scale;

Fig. 2 is a plan view in larger scale of a portion 15 of the winding machine illustrated in Fig. 1, showing several of the winding units and the drive therefor;

Fig. 3 is a front elevation of the same, showing 15 three of the winding units as operative and one of the units as inoperative; and

Fig. 4 is a vertical sectional view of a portion of 20 the machine taken on line 4—4 of Fig. 3.

The present improved winding machine comprises, in general, a circular rail or trackway supported on columns or stanchions; an annulus revolvable on the trackway for traveling a plurality of winding head or units in a closed course; driv- 25 ing means for revolving the annulus on the track- way; a unitary driving means for operating the individual winding mechanisms during their travel around the trackway; means incorporated in the last-named driving means for effecting a 30 periodic alteration in the speed of one of the winding elements; and automatic stopping mechanism for controlling the operation of the individual winding units.

Referring to the drawings, the improved wind- 35 ing machine as herein shown embodies a unit- supporting annulus or ring 2 which is preferably of inverted channel-shape in cross section, see Fig. 4, and supported to revolve upon a circular rail or trackway 3. The rail 3 has over- 40 hanging side lugs 4 resting upon the upper end of columns or stanchions 5 which may be constituted by lengths of piping mounted for vertical adjustment in feet or bases 6 secured to the floor. The rail 3 is of angular shape in cross section 45 with its horizontal flange provided with a finished face 7 upon which the annulus 2 is revolvably mounted by means of rollers 14 to be later described. The vertical flange of the angular rail 3 is secured to the upper end of the columns 50 5 by means of U-bolts 8 looped therearound and fastened to the rail by nuts 9. Preferably, the rail-member or trackway 3 and the annulus 2 are constituted by a plurality of arcuate sections bolted together at 10 and 11, respectively, as 55

shown in Fig. 2, to adapt them for economical manufacture and convenient assembly. Journaled in bosses or bearings 12 formed integral with the outer flange of the channel-
5 iron annulus 2 are stud-shafts or axles 13 carrying the rollers or traction wheels 14 which travel upon the finished upper face 1 of the trackway 3 when the annulus is revolved in the manner as later explained. The annulus 2 is formed on its inner flange with a plurality of bosses or
10 lugs 16 to which is attached, by means of bolts 17, a ring-gear 18 having rack-teeth cut in its upper face.

The driving means for revolving the annulus 2 is preferably positioned within the circumference of the latter and may comprise an electric motor, such as shown at 20, arranged for vertical adjustment upon a bed or platform 21. As illustrated in Figs. 3 and 4, the platform 2 is constructed in the form of a rectangular plate supported from the floor by legs or standards 22 bolted thereto. Referring to Fig. 2, the armature-shaft of the motor 20 is connected by means of a coupling 23 to the end of a stud-shaft 24 forming one of the rotative elements of a speed-reducing mechanism, indicated generally by the reference character 25. The speed-reducing mechanism may be of conventional type and therefore will not be herein described in detail. Suffice it to state that a pinion 26 fast on the shaft 24 meshes with a larger gear 27 fixedly secured to a shaft 28, both shafts being journaled in bearings on the sides of a covered box or casing 29. The shaft 28 carries at its forward end a pinion-gear 30, the teeth of which mesh with the teeth of the ring-gear 18 previously mentioned. It will be understood that when the electric motor 20 is operative power will be transmitted therefrom to the shaft 28 through the gears 24 and 27 and the pinion-gear 30 meshing with the ring-gear 18 will revolve the annulus 2 at a greatly reduced rate of speed. Any suitable electric switch, for example, of the push-button type, may be provided for controlling the starting and stopping of the motor and thereby the turning movement of the annulus 2.

The winding units or heads, designated generally by the reference character 35, are removably mounted upon the annulus 2 to be traveled thereby past the operator's station. Any suitable type of winding unit may be mounted on the revolving bed or annulus 2, the mechanism herein illustrated by way of example being similar in construction to that shown and described in my pending application for United States Letters Patent, Serial No. 447,588, filed April 26, 1930, now Patent No. 1,895,741, issued Jan. 31, 1933. As shown most clearly in Figs. 2 and 4 of the present drawings, each winding unit 35 is mounted on a bracket or standard 36 detachably fastened to the upper face of the annulus 2 by means of bolts 37. An outboard bearing member 39 is positioned outwardly with respect to the bracket 36, being supported in spaced parallel relation thereto by means of tie-rods or spacer-studs 40. The members 36 and 39 carry the bearings for the driving shaft and also support the other parts of the winding mechanism.

In the present construction of the machine 70 each winding unit comprises only two principal operating elements, namely, the winding-mandrel or spindle 43 on which the cop-tube C, or other core for the package is rotatably supported and the drive-roll 45 for rotating the yarn-receiver; and in which is embodied the means

for traversing the yarn back and forth axially of the package being wound. In this form of construction the usual reciprocating thread-guide is dispensed with and the drive-roll 45 has its peripheral surface provided with connected helical grooves 46 and 47 extending in opposite directions and adapted to receive the strand of yarn to guide it back and forth between the ends of the package. This particular form of traversing means is shown and described in United States Letters Patent No. 1,749,355 dated March 4, 1930. It is to be understood, however, that various other types of winding mechanisms may be employed as units on the revolvable annulus 2, such for example, as that wherein the package is driven by contact with a drive-roll and the yarn traversed by means of a reciprocating thread-guide.

In the present form of construction the drive-roll 45 is carried on and rotated by a horizontal shaft 48 journalled in bearings 49 and 50 supported by the members 36 and 39. Fast on the inner end of the shaft 48 abutting the side of the bearing 49 is a pulley or drive-wheel 51 adapted to be rotated by peripheral contact with a friction drive-ring 52 which is revolved about the axis of the machine in the manner as later more fully explained.

The winding units of the machine are herein shown as adapted for winding packages P of 30 conical form in which the yarn is built up on an axial core or support, for example, a paper or fiber cone-tube C illustrated in Fig. 4 as rotatively mounted on the winding-spindle or mandrel 43 by means of a cop-tube holder 44. The winding-spindle 43 is fixedly connected at its inner end to the forked end of an arm or rod 53, the opposite end of which is swiveled in a bearing 54 on a Y-shaped arm or lever 55. The arm 55 is hinged on a rod 56 held in a bearing 51 40 projecting from the top of the bracket 36 of the next adjacent winding unit in the series. The arm 55 is usually weighted whereby to cause the surface of the yarn-receiver or cop-tube C, or the surface of the package P, as the case 45 may be, to be held in driving contact with the periphery of the drive-roll 45, and as the yarn is built up on the cop-tube C it forces the latter upwardly with the arm 55 pivoting on the rod 56.

A common driving member for the whole series 50 of winding units drives the individual shafts 48 through means as next described. As above explained, the shafts 48 are adapted to be rotated in their bearings by the traction engagement of their pulleys or wheels 50 with the lower face 55 of the drive-ring or friction annulus 52. The drive-ring 52 rests upon and is supported solely by the pulleys 50, being held to its circular orbit by means of flanges or rims 58 on the pulleys engaging its outer edge or rim, see Fig. 4. The bottom face of the ring 52, which constitutes the driving surface engaging with the pulleys, may be coated with a suitable friction material for providing the maximum traction. Spaced at intervals along the bottom driving surface of the 65 friction-ring 52 are a series of gaps or recesses 59 provided for a purpose as later explained.

In operation, the winding units are traveled about the axis of the machine in a contraclock-wise direction as viewed in Figs. 1 and 2. If the 70 friction-ring 52 were held stationary, the pulleys 50 would nevertheless travel upon its under surface to cause the shafts 48 and the drums or drive-rolls 45 to be rotated. However, to secure a sufficiently rapid speed of the drive-rolls 45 75

to effect maximum production of the winding units it would be necessary to revolve the units about the machine at a rate too fast for attention as they pass the operator's station.

Therefore, to provide for high speed rotation of the drive-rolls with a relatively slow rate of travel of the winding units themselves, the friction driving ring 52 is turned clockwise, as viewed in Figs. 1 and 2, or in a direction opposite to the direction of revolution of the annular bed or support 2 for the units. The speed of rotation of the drive-rolls is thus greatly multiplied and the productiveness of the winding mechanism accordingly increased. The means for turning the friction drive-ring 52 is organized and arranged as next described.

The drive-ring 52 is provided on its top with teeth and meshing therewith is a pinion 60 fast on the armature-shaft of a second electric motor 61. As shown in Fig. 4, the motor 61 is adjustably supported upon the platform 21, previously described, with its axis arranged radially with respect to the axis of the ring 52. The starting and stopping of the motor 61 may be effected by a push-button operated switch, not herein shown, arranged in circuit with the motor 20, if desired, and its rotative speed is governed by suitable controlling mechanism as usually provided.

Means are provided in the present improved winding machine for disrupting the synchrony of motion between the rotating package and the traverse mechanism for the yarn, such a device being known as a "ribbon-breaker" for controlling the disposition of the turns of winding on the surface of the package to prevent the coils of yarn from crowding or "piling". As is well known to those versed in the art of drum winding, when the cop-tube or other yarn-receiver is first started to rotate to wind on the yarn the coils are usually laid in "open" or spaced relationship; but when the "wind" changes due to the constantly increasing diameter of the package, the coils gradually close up and eventually tend to crowd or "pile" on each other to cause what is termed a "ribbon wind" on the surface of the package. Where several coils are laid over each other in the "ribbon" they tend to slip or slide out of place, thus disturbing the twist of the yarn to such an extent that its quality is impaired and, in addition, the free delivery of the yarn from the package is hampered. In order to overcome this defect in the winding operation the present invention contemplates the provision of means incorporated in the drive-ring 52 for periodically altering the speed of rotation of each drive-roll 25 to disrupt the synchronism between the package and the traversing yarn.

As before mentioned, the friction-ring 52 is provided with a series of gaps or recesses 59 in its driving face spaced at intervals around its circumference, see Fig. 3. During operation of the machine the pulleys 50 contact with and are rotated by the bottom face of the ring 52 in the manner as above explained. As the annulus 2 and the ring 52 are revolved in opposite directions the recesses 59 come successively into opposition with the different pulleys 51. At such juncture the driving contact between the ring 52 and the pulley 51 opposite its recessed portion momentarily ceases so that the drive-roll, while continuing to rotate under the influence of momentum, will have its speed checked or retarded. The period of deceleration in the speed of the drive-roll is of relatively short duration, and as the ring 52 continues to revolve the recessed portion 59 is car-

ried past the pulley 51 so that the latter once more engages the lower face of the ring and its speed is accelerated to the maximum again. As shown in Fig. 3, the ring 52 is provided with a recess 59 for each five winding units, but this number is arbitrary and may vary according to requirements.

The yarn is supplied to the winding units from bobbins b held on spindles 63 located beneath and slightly in advance of the winding spindles. An arm or bracket 64 is secured to the tie-rods 49 of each unit and reaching downwardly therefrom its lower extremity supports the supply-spindle 63 pivoted thereto, see Figs. 3 and 4. The yarn is drawn upwardly through a suitable tension-device, indicated generally by the reference character 65, across a stationary guide 68 and a movable bail-wire 66 which forms a part of the stopping mechanism of the winding unit. The bail-wire 66 constitutes a means for actuating the stopping mechanism when the yarn breaks or its supply becomes exhausted and, as herein shown, the wire is pivoted at 67 to one end of a guard-member 69, the latter, in turn, being hingedly mounted between the bracket 36 and outboard bearing 39. At the opposite end of the guard-member 69 is a pivoted knock-off lever 70, the lower end of which is normally held raised above the path of a series of stationary cam-plates 71 secured to the forward rim of the rail or track-way 3 by means of screws 72.

The knock-off lever 70 is held in raised position by a suitable connection with the bail-wire 66 in the manner described in my copending application, Serial No. 447,583, hereinbefore referred to. When the yarn breaks or its supply is exhausted the bail-wire 66 swings outwardly and releases the knock-off lever 70, thereby permitting the latter to drop into position to engage with one of the stationary cam-plates 71. As the winding unit revolves the lever 70 rides up the curved edge of the cam 71 and the guard member 69 is swung on its pivot. The member 69 has a ratchet connection with a bar 74, termed the "sizing bar", which is attached at 75 to a depending portion of the spindle-arm 55. As the bar 74 is drawn forward by the rocking motion of the member 69 the arm 55 is raised to swing the winding spindle 43 upwardly and thus disrupt the driving contact between the drive-roll 45 and the package P being wound. The arrangement and method of operation of the parts of the stopping mechanism above described are substantially the same as more fully set forth in the application previously referred to. The sizing bar 74 also constitutes one of the elements of the sizing mechanism for actuating the stopping mechanism when the package being wound reaches a predetermined size; but as this part of the machine is substantially identical with that disclosed in the above mentioned application it is unnecessary to describe it in detail.

For starting the operation of each individual winding unit a handle or starting lever 76 is provided on the bar 74 whereby the latter may be released from its ratchet to return the parts to position with the package held in driving contact with the periphery of the drive-roll. The method of operation of the complete winding machine is as next explained.

The machine is started to operate by energizing the electric motors 20 and 61 through the means of a switch or switches, not herein shown. The motor 61, through its geared connection with the friction-ring 52, revolves the 75

latter in a clockwise direction as viewed in Figs. 1 and 2, and the pulleys or wheels 51 are driven by rolling contact therewith to rotate the drive-rolls 45. The motor 20 which is connected through the reducing gearing 25 to the ring-gear 18 revolves the latter in the opposite direction to travel the winding units around the machine. With the dual arrangement of motors as above described the winding units are caused to travel around the machine at a slow rate of speed with the drive-rolls 45 turning at high speed to perform the winding on the cop-tubes C rotated therefrom. When the yarn feeding to a unit breaks or its supply is exhausted, or upon completion of the package, the operation of this unit is immediately arrested by the automatic stopping mechanism. Then, as the nonfunctioning unit is brought around past the operator's station, the break in the yarn is repaired, a new bobbin supplied if necessary, or the completed package doffed and a fresh one started, as the case may be. The operator may take up a position at any desired point around the circumference of the machine, this point being indicated at X in Fig. 1. The operator is usually provided with a suitable seat and furnished with a supply hopper for holding the full supply-bobbin bins, a box for receiving the spent bobbins and a rack upon which the wound packages are stacked.

Each unit or head is prepared for winding by mounting a wooden or fiber cop-tube or yarn-receiver C to rotate on the spindle 43 while the latter is held in raised position as shown at the left in Fig. 3. The strand of yarn y or other material is led upwardly from its source of supply b through the tension-device 65, thence drawn across the guide 68 and bail-wire 66 to the periphery of the drive-roll 45 and its end fastened to the cop-tube C. After the strand is secured to the cop-tube the operator lifts the starting handle 76 and the arm 55 is lowered to bring the surface of the receiver C into driving contact with the periphery of the drive-roll 45. As the yarn-receiver C is brought into peripheral contact with the drive-roll 45 it will be rotated from the roll to wind on the yarn. The roll 45 turns in the direction indicated by the arrow in Fig. 3 and as the yarn is taken up by the rotation of the cop-tube C the strand y will enter one or the other of the crossing helical grooves 46 and 47 on the periphery of the roll. As the yarn feeds through the grooves it is traversed thereby back and forth longitudinally of the cop-tube to deposit it thereon in helical coils which make several turns first in one direction and then in the opposite direction from end to end of the package being wound. In this way the yarn is given a continuous traverse from one end of the cop-tube to the other end and back again to build up a succession of courses forming overlying layers which constitute the yarn body or package P.

As above explained, the drive-roll 45 is rotated by frictional contact of the pulley 51 with the drive-ring 52 and as the latter revolves the recessed portions or gaps 59 therein serve to periodically interrupt the driving contact. As the speed of the drive-roll is retarded the momentum of the package will cause it to run ahead with its surface slipping on the roll and in this manner the synchrony of motion between the package and the roll, which latter constitutes the traversing means, is disrupted. By thus periodically changing the ratio of speed between the rotation of the package and the traverse of

the yarn "ribbon winding" is prevented in the same manner as described in my pending application for United States Letters Patent, Serial No. 552,282, filed July 21, 1931, now Patent No. 1,899,651, issued Feb. 28, 1933.

The operator starts each individual winding unit as the latter are successively carried to the station X. Sufficient time is allowed as the unit slowly passes the station to enable the operator to replenish the supply and tie up the end; or 10 to doff a full package and place a new cop-tube on the holder when required. The winding units are continuously traveled in a closed course in the manner explained and after the last unit in the series has been started the initially started 15 unit again reaches the station X. Preferably, the rate of travel of the units is so timed that the yarn will be consumed from one supply bobbin during each course of the unit around the machine. The exhaustion of the supply occurs just 20 prior to the arrival of the unit at the station and the stopping mechanism acts to raise the package away from the periphery of the drive-roll 45 to arrest the winding operation. Following the stopping of the winding mechanism the 25 unit enters the station X and the operator places a fresh supply-bobbin b on the spindle 63 and ties its end to the strand already wound into the package and starts the winding operation again. This is accomplished by the simple act 30 of raising the starting handle 76 to lower the package into peripheral contact with the drive-roll 45. It will be understood that a plurality of the cam-plates 71 are arranged about the 35 rail 3 at short intervals to provide that if the 40 yarn breaks at any point during the travel of a unit the winding operation thereof will be promptly arrested. When the packages are completed they are doffed and the units prepared and started to operate again in the manner as previously explained.

It will be observed from the foregoing that the present invention provides a highly efficient means for traveling a series of winding units in a closed course to successively present them to 45 an operator for "tending" at a fixed station. The operator may thus sit comfortably at the station and perform the necessary operations with a minimum of exertion, thus reducing fatigue and greatly increasing the productive 50 capacity of the machine. By the saving of time usually required for walking up and down along the machine frame the operator may attend a greater number of units with a further increase 55 in efficiency.

The winding units are detachably mounted upon the revolvable annulus so that they may be removed therefrom for repair or replacement without necessitating interruption in the operation of other units in the series for any considerable period.

The machine is extremely simple in construction, adapted for easy assembly of the parts and practically proof against derangement or getting out of order.

While I have herein disclosed a preferred form of construction of the machine, various modifications may be made in the structure and arrangement of its parts without departing from the spirit or scope of the present invention. 70 Therefore, without limiting myself to the exact embodiment shown and described, I claim:

1. In a winding machine, the combination of a circular trackway, an annulus revolvable on the trackway, a plurality of winding units mount- 75

- ed on the annulus and comprising means for rotatably supporting a package on each unit, a drive-ring arranged concentric with the annulus, shafts journaled on the annulus, drive-rolls 5 driven from said shafts for rotating the packages, and means on said shafts engaging the drive-ring to support the latter and rotate the drive-rolls of the winding units during their travel with the annulus.
- 10 2. In a winding machine, the combination of a circular trackway, a plurality of winding units, means for rotatably supporting a package on each winding unit, means for traveling the winding units on the trackway, drive-rolls for driving the packages of the individual winding units, a drive-ring arranged concentric with the trackway, means connected with the drive-rolls and engaging the drive-ring to support the latter and rotate the rolls, and means for revolving the drive-ring in a direction opposite to the direction of travel of the winding units.
- 15 3. In a winding machine, the combination of a circular trackway, an annulus revolvable on the trackway, a plurality of winding units mounted on the annulus, shafts journaled on the annulus, drive-rolls on said shafts, means for rotatably supporting packages in driving contact with the rolls, pulleys on said shafts, and a drive-ring supported on the pulleys concentric with the annulus and engaging the peripheries of the pulleys to drive the shafts.
- 20 4. In a winding machine, the combination of a circular trackway, an annulus revolvable on the trackway, a plurality of winding units mounted on the annulus, means on each unit for rotatably supporting a package, shafts journaled on the annulus, drive-rolls on said shaft for driving the packages, a drive-ring supported from said shafts concentric with the annulus, means on the shafts engaging the drive-ring, and means to revolve the drive-ring in a direction opposite to the direction of revolution of the annulus.
- 25 5. In a winding machine, the combination of a circular trackway, an annulus revolvable on the trackway, means for revolving the annulus, a plurality of winding units mounted on the annulus to be traveled thereby in a closed course, means on each unit for rotatably supporting a package, drive-shafts for the winding units, drive-rolls driven from said shafts, pulleys on said shafts, a friction drive-ring resting on the pulleys concentric with the annulus to effect driving contact with the peripheries of the pulleys, and means to revolve the drive-ring in a direction opposite to the direction of revolution of the annulus.
- 30 6. In a winding machine, the combination of an annular trackway, an annulus revolvable on the trackway, means to revolve the annulus, a plurality of winding units carried on the annulus to be traveled in a closed course, shafts for driving the winding units, pulleys on said shafts, a drive-ring arranged concentric with the annulus and supported on the pulleys to provide frictional contact with their peripheries, and means for revolving the drive-ring in a direction opposite to the direction of travel of the winding units.
- 35 7. In a winding machine, the combination of a circular trackway, an annulus revolvable on said trackway, an annular gear-rack carried on the annulus, a pinion engaging the gear-rack, a motor for driving the pinion to revolve the annulus, shafts for operating the winding units, pulleys on said shafts, a friction drive-ring arranged concentric with the annulus in engagement with the peripheries of the pulleys and provided with gear-teeth, a pinion engaging the gear-teeth on the drive-ring, and a motor for driving said pinion to revolve the drive-ring in a direction opposite to the direction of movement of the annulus.
- 40 8. In a winding machine, the combination of an annular trackway, an annulus mounted above the trackway, rollers between the annulus and the trackway, a plurality of winding units mounted on the annulus, a gear-rack on the annulus, a pinion engaging the teeth of the rack, a motor for driving the pinion, shafts journaled on the annulus for operating the winding units, a drive-ring for rotating the shafts, and means to revolve the drive-ring in a direction opposite to the direction of movement of the annulus.
- 45 9. In a winding machine, the combination of a circular trackway, stanchions for supporting said trackway from the floor, an annulus revolvable on the trackway, a motor, gearing connecting said motor to revolve the annulus on the trackway, a plurality of winding units carried on the annulus, shafts for driving the winding units, an annular drive-ring arranged concentric with the annulus and connected to drive the shafts for the winding units, and a second motor for revolving the drive-ring in a direction opposite to the direction of movement of the annulus.
- 50 10. In a winding machine, the combination of a circular trackway, an annulus revolvable on the trackway, a motor, gearing connecting the motor to revolve the annulus, a plurality of winding units carried by the annulus, shafts journaled on the annulus for driving the winding units, a drive-ring for driving said shafts, a second motor, and gearing connecting the second motor to revolve the drive-ring.
- 55 11. In a winding machine, the combination of a circular trackway, a plurality of winding units, means for traveling the winding units in a closed course on the trackway, a shaft for each winding unit, drive-rolls driven by said shafts, means for supporting packages in surface contact with the drive-rolls, a drive-ring supported on the shafts of the winding units concentric with the trackway, and means engaging the drive-ring to rotate the drive-shafts.
- 60 12. In a winding machine, the combination of a plurality of winding units, means for traveling said units in a closed course, a drive-roll for each unit, individual driving means for each drive-roll, an annular drive-ring common to all of said units and supported solely from the driving means thereof to rotate the drive-rolls, and means to revolve said drive-ring in a direction opposite to the direction of travel of the units.
- 65 13. In a winding machine, the combination of a plurality of winding units, means for traveling said units in a closed course, separate driving means for the individual units, a drive-ring engaging said driving means, means to revolve said ring to drive the driving means for the units, and means to periodically interrupt the drive between the ring and the unit-driving means to disrupt the synchronism of the drive.
- 70 14. In a winding machine, the combination of a plurality of winding units, means to travel said winding units in a closed course, individual driving shafts for the units, a drive-ring common to all of the units, and means on the driving shafts engaging the drive-ring to operate the units, said drive-ring having gaps therein spaced at intervals of its circumference whereby to interrupt the driving connection with the shafts to cause a periodic deceleration in the speed of the shafts.

15. In a winding machine, the combination of means for rotatably supporting a package, a drive-roll for rotating the package by peripheral contact therewith, a shaft for rotating the drive-roll, and a drive-element engaging the driving means on the shaft, said drive-element having a plurality of spaced gaps for interrupting the driving engagement whereby to periodically alter the rate of speed of the shaft and the drive-roll rotated thereby. 5
16. In a winding machine, the combination of means for rotatably supporting a package, means for rotating the package, traversing means for distributing the yarn on the package, a shaft for operating the traversing means, a driving element on said shaft, and a drive-element engaging said driving element to drive the shaft, said drive-element having gaps in its engaging surface whereby to interrupt the driving engagement to periodically alter the speed of rotation of the shaft and the traverse mechanism operated thereby. 10
17. In a winding machine, the combination of means for rotatably supporting a package, a drive-roll for rotating the package, means for traversing yarn on the package, a driving shaft, a driving wheel on said shaft, and a drive-element engaging the wheel to rotate the shaft, said drive-element provided with a plurality of gaps in its driving face whereby to interrupt its driving engagement with the wheel to periodically alter the rate of speed of the driving shaft. 15
18. In a winding machine, the combination of means for rotatably supporting a yarn-package, a drive-roll for rotating the package by peripheral contact therewith, and means to drive the drive-roll, said driving means having a plurality of gaps in its driving surface whereby to interrupt the drive to periodically alter the speed of the drive-roll to disrupt the synchronism between the package and its traversing means. 20
19. In a winding machine, the combination of means for rotatably supporting a yarn-package, a grooved traverse-roll for rotating the package by contact with the periphery thereof while acting to traverse the yarn longitudinally thereon, and means to drive the traverse-roll, said means having an interrupted driving face formed with gaps to produce changes in ratio between the speed of the package and the traverse of the yarn to prevent ribbon winding. 25
20. In a winding machine, the combination of means for rotatably supporting a yarn-package, a drive-roll for rotating the package by peripheral contact therewith, means for traversing yarn on the package, a driving element, and means engaging the driving element to impart rotation to the drive-roll, said driving means having gaps in one of the driving faces to periodically interrupt the driving contact whereby to change the ratio between the speed of the package and the traverse of the yarn to prevent ribbon winding. 30
21. In a winding machine, the combination of an annular trackway, an annulus supported from the trackway to revolve therearound, a plurality of winding units carried on the annulus, means on each winding unit for supporting and driving a package, shafts for said package-driving means, a drive-ring arranged concentrically with the annulus and supported from the drive-shafts, and power means for revolving the annulus and drive-ring in opposite directions. 35
22. In a winding machine, the combination of an annular trackway, an annulus revolvable on said trackway, means for revolving said annulus, a drive-ring arranged concentric with and supported from the annulus, winding units carried by the annulus, a drive-shaft for operating each winding unit, means connecting the drive-ring to rotate the shafts, and power means for revolving the annulus and drive-ring in opposite directions 40
23. In a winding machine, the combination of a plurality of winding units, a drive-roll for each winding unit, means for rotatably supporting a package in contact with each drive-roll, means for traveling the winding units in a closed circuit, means for driving the drive-rolls, and means to periodically interrupt the connection between the driving means and drive-rolls during the travel of the winding units to vary the speed of the drive-rolls to prevent ribbon winding. 45
24. In a winding machine, the combination of a plurality of winding units each comprising a drive-roll and means for supporting a package in driving contact with the roll, means for traveling said units in a closed circuit, and driving means for transmitting rotation to the drive-rolls, said driving means having gaps to interrupt the driving connection to periodically vary the speed of the drive-rolls whereby to prevent ribbon winding. 50
25. In a winding machine, the combination of a plurality of winding units each comprising a drive-roll with means for rotatably supporting a package in contact with the drive-roll and means for traversing yarn on the package, means for traveling said units in a certain direction in a closed circuit, driving means traveling in the opposite direction in the circuit and operating to transmit rotation to the drive-rolls, and means to periodically interrupt the connection between the driving means and drive-rolls to vary the speed of the latter whereby to prevent ribbon winding. 55
26. In a winding machine, the combination of a plurality of winding units, means to travel said units in a closed circuit, means for driving the winding units during their travel, and means to periodically interrupt the driving connection to vary the winding speed to prevent ribbon winding. 60
